DIRECTIONAL RADIO SYSTEM

William P. Lear, Dayton, Ohio, assignor, by mesne assignments, to Lear Avia, Inc., Piqua, Ohio, a corporation of Illinois

Application December 28, 1940, Serial No. 372,059

6 Claims. (Cl. 250—11)

This invention relates to radio direction finding systems and more particularly to automatic radio direction indicators, being a continuation-in-part of my copending application "Automatic radio direction indicator," Serial No. 286,733, filed on July 27, 1939, now Patent No. 2,308,521, issued Jan. 19, 1943 and assigned to the same assignee.

The automatic radio direction finder to which this invention relates employs a reversible electric motor controlled by the received radio signals for rotating a directional antenna into bearing relationship with the incoming radio waves. The directional antenna is generally a rotatable loop mounted on the exterior of the aircraft for efficient signal reception. A 360° indicator is mechanically coupled to the driven directional antenna to indicate its angular position and azimuthal bearing.

In accordance with the present invention, the control motor is arranged remote from the directional antenna, being incorporated in the electrical control compartment. As will be set forth in detail hereinafter, locating the control motor within a shielded chassis close to its electrical control circuits, eliminates the prior electrical cables and thereby electrical interferences with signal reception or the magnetic compass. The interference generally was manifest as switching clicks and commutator noise, or other electromagnetic waves radiated by the connecting cable. Furthermore, the motor is subjected to far less variation in temperature than when located adjacent the externally mounted loop antenna as heretofore. The result is a more stable operation.

Another important feature of the present invention resides in the novel construction of the loop control motor. A pronged plug-in construction is incorporated with the motor at its base, for readily mounting it in position as well as effecting its electrical connection with the circuits. The plug-in construction greatly simplifies servicing and maintenance of the motor in the field. Since this control motor is an important unit that is checked at regular servicing intervals, the arrangement of the invention eliminates costly and time consuming operations required heretofore. The whole motor drive assembly including an integral electromagnetic clutch is readily dismounted and disconnected from its circuit simply by removing a few mounting screws.

These and other advantages, capabilities, and features of the invention will appear from the following detailed description of a specific em-

bodiment thereof, illustrated in the accompanying drawings, in which:

Fig. 1 is a diagrammatic illustration of the system, in perspective, showing coaction of the components.

Fig. 2 is a front elevational view showing the loop drive unit on the chassis.

Fig. 3 is a side elevational view of the mounted loop control drive and motor.

Fig. 4 is a rear elevational view of the loop motor socket and connections.

Fig. 5 is a side elevational view, partly in section, of the loop control motor of the invention.

Fig. 6 is an end view of the motor of Fig. 5.

The automatic radio directional system, diagrammatically shown in Fig. 1, comprises a control unit 10, a radio and electrical control circuit unit 15, and rotatable directional antenna 20. Antenna 20 is a rotatably mounted loop within streamline housing 21 supported on neck 22. The antenna assembly is arranged on shell 23 of the aircraft, extending above or below the aircraft fuselage to insure efficient pick-up of the radio signals. The control unit or head 10 is placed near the pilot for remotely operating the direction finder system.

Chassis unit 15 contains the requisite radio and control circuits for the system, being generally located remote from the loop antenna, at a convenient accessible place for its maintenance and servicing. Patent No. 2,308,521 referred to hereinabove discloses appropriate circuits for effecting the automatic radio directional operation. A 360° indicator 25 is coupled to the direction finder system, being placed near the pilot for indicating the bearing position of loop 20.

A band selector switch 30 is provided on control head 10 for adjusting the radio circuits in units 10 and 15 to the desired band of radio frequency operation. Selector switch 30 simultaneously shifts shutter mask 31 of radio tuning indicator 32 in correspondence with the band selected. Details of this arrangement appear in my copending application, Serial No. 378,490, entitled "Radio tuning mechanism" filed on Feb. 12, 1941. Tuning knob 33 operates a slide-rule type frequency scale 34 to indicate the frequency of the radio station tuned-in opposite stationary index 35. Tuning knob 33 at the same time rotates mechanical cable 36 coupled to the variable radio frequency condenser bank within chassis unit 15 for correspondingly tuning the contained direction finder circuits. A tuning meter 37, in circuit with the radio system, apprises the pilot of the optimum tuning conditions. The mode of

circuit operation for the direction finder system is controlled by switch lever 38 of control head 10. The gain level of the system is adjusted by knob 39. The electrical connections between control head 10 and chassis unit 15 comprise junction box 40 and electrical cables 41, 42.

Chassis unit 15 obtains a removable metallic casing 43 and front panel 44. Reference is directed to my copending application Serial No. 354,653, filed on August 29, 1940, now Patent No. 2,309,323 issued Jan. 26, 1943, for preferred construction of this unit. The non-directional antenna 45 is connected to insulated terminal 46 on the front of unit 15. The master on-off switch 47 for the direction finder system is arranged on panel 44, remotely from control head 10. The power supply for the system is conducted through cables 42 and 48 via junction box 40. In this manner, the relatively high amperage current for the system does not pass through the aircraft or adjacent the instrument panel, avoiding any effects on the magnetic compass.

The loop winding 20 is of low impedance, and electrically connected to radio circuit unit 15 by low impedance shielded cable 49 through junction box 40 and cable 42. Connection between cable 49 and the rotatable loop antenna is afforded through slip rings. A quadrantal error corrector unit 50 is coupled between the rotatable loop antenna 20 and mechanical shaft 51 which operates the loop, in a manner such as indicated in my copending application, Serial No. 344,854, filed on July 11, 1940, and assigned to the same assignee.

Loop drive shaft 51 is directly coupled to a drive unit 52 mounted on panel 44 of chassis unit 15, by flexible shaft 53 and shaft 54 of an H-coupling unit 55. Shaft 53 is removably coupled to motor drive unit 52 by nipple arrangement 56. Electrical cable 42 is removably coupled to socket 57 on panel 44 through multiple plug 58. Control head shaft 36 is removably coupled to panel 44 by coupling piece 59. Chassis unit 15 may accordingly be readily uncoupled both electrically and mechanically from the remainder of the direction finder system for greatly facilitating its maintenance and servicing in the field.

An important feature of the present invention resides in arranging the loop drive system 52 in the control chassis unit 15, remote from the rotatable loop antenna 20. The motor is electrically shielded by housing 43. The cable connections to the motor are short and direct, and wholly within unit 15. No motor circuit connections are required between control unit 15 and the remotely positioned loop 20, thereby avoiding interference with the magnetic compass, or with the radio reception. Radiation of clicking and commutator noises is eliminated.

The loop antenna 20 is directly mechanically driven by drive unit 52 through flexible mechanical shafting 51, 53 joined at H-coupling unit 55. Bearing indicator 25 is mechanically coupled to the mechanical loop drive system by flexible shaft 60 connected with shaft 61 of H-unit 55. Shafts 54 and 61 of H-unit 55 are connected by 1:1 gearing 62, 63. Indicator shaft 60 is accordingly positively related with motor drive shaft 53, following in phase with shaft 51 that controls the angular position of loop antenna 20. Pointer 64 of indicator 25 is directly geared to shaft 60 in the same ratio that the loop antenna 20 is geared to drive shaft 51. The angular relation between loop antenna 20 and needle 64 is initially adjusted so that indicator 25 shows the proper

azimuthal bearing positions of the loop. The quadrantal error corrector unit 50 automatically compensates the bearing indications for extraneous radio distortions, in a manner well known in the art.

Another feature of the invention resides in arranging a plurality of indicators for the bearing positions. Besides indicator 25, there is the second indicator unit 65, containing a radio bearing index 66. Index 66 is connected to H-coupling unit 55 through mechanical shaft 67. Indicator 65 coaxially coordinates the radio bearing indications with those of a gyro-compass within unit 65, in the manner disclosed in my copending application Serial No. 314,672 filed on January 19, 1940, and assigned to the same assignee. A gear ring supports index 66 and engages with a pinion at 68 in the ratio equal to the gearing between loop antenna 20 and drive shaft 51, for in-phase driving therewith by shaft 67. The respective mechanical transmission shafts 51, 53, 60 and 67 are individually removably coupled to H-unit 55 through coupling nipples 69. It is to be understood that additional mechanical coupling units may be connected to drive shaft 53 or to any of the individual mechanical drive shafts, for operating additional remote indicators of the loop bearing positions.

The 360° quadrantal error corrector 50 provided between loop antenna 20 and the plurality of bearing indicators and motor drive unit 52 affords the accurate azimuthal bearing indications at a plurality of positions on the aircraft. The indicators are thus individually interchangeable or removable, without affecting the operation of the remaining indicators. Coupling nipples 69 of H-unit 55 permit the convenient addition of an indicator if only one has been installed. Furthermore, when remote motor drive unit 52 is disassembled for servicing, the several indicators, 25 and 66, remain in-phase relation with the loop antenna 20 and corrector 50, and need not be tested or readjusted after the servicing.

A manual loop drive crank 70 is mechanically connected to indicator 25 and its drive shaft 60 through the connection 71 indicated in dotted lines. In the event that manual direction finding operation is indicated in flight, such as when the electric motor control unit 52 is disconnected or inoperative, direct drive of loop 20 and the associated radio indices 64 and 66 is effected through crank 70. Aural or visual null signal reception is then used with the system. Crank 70 is normally unclutched from connection 71 to prevent its rotation during automatic directional operation. An adjusting knob 72 is coupled to bearing scale 73 for displacing it from its indicated "zero" position whenever desired during navigation.

In accordance with the present invention, the control motor drive unit 52 is mounted for ready removal from panel 44. Figs. 2 and 3 show details of its construction. Motor control unit 52 comprises a reversible electric motor 75, an electromagnetic clutch unit 76 and a reduction gearing unit 77, forming a mechanically interconnecting integral device. Mechanical cable 53 is detachably connected thereto through fluted output shaft 78 being held in position by nipple 56 threaded onto threaded projecting tube 59. Metallic prongs 80 project from insulated base 81 at the end of motor 75, and engage with split metallic receptacle members 82 of socket 83. Socket 83 is attached to supporting frame 84 extending from panel 44.

The mounting of motor drive assembly unit 52 is secured merely by screws 85 extending through gear unit 77 and engaging with panel 44. The rear of drive assembly 52 is mechanically supported by the four projecting prongs 80 engaged with socket 83. By loosening screws 85, unit 52 including integrally connected motor 75, clutch 76 and gearing 77, is slipped off panel 44. The electrical connections to the motor 75 and clutch 76 are made through prongs 80 to electrical cable 87 via socket 83 including its pronged members 82 and connecting lugs 86, as shown in Figs. 3 and 4. Electrical cable 87 and socket 83 remain stationary within the chassis and with respect to internal supporting frame 84. The motor 75 and clutch 76 are accordingly readily electrically disconnected from the circuit when uncoupled in the manner herein set forth.

Figs. 5 and 6 show further details, in cross-section, of motor drive unit 52. The illustrated motor 75 is of the reversible direct current type such as used in the automatic direction finder circuit disclosed in Patent No. 2,308,521 referred to above. It is to be understood, however, that a different type electric motor, such as an alternating current one, may instead be used. Direct current motor 75 has a commutator 88 and brushes 89. Metallic prongs 80 projecting from motor 75 are in suitable electric connection with the brushes and field coils of the motor, as well as with energizing winding 90 of electromagnetic clutch 76.

Suitable electrical connections for the motor 75 and clutch 76 are indicated in Patent No. 2,308,521, as well as in my copending application, Serial No. 346,542 filed on July 20, 1940 now Patent No. 2,267,114 issued Dec. 23, 1941. The electrical cable connection to the motor and clutch therein shown are replaced by prongs 80, in a manner which will now be evident to those skilled in the art. It is to be understood that prongs 80 afford electrical connections for motor 75 and clutch 76 with the electrical control circuits of unit 15 via cable 87. The prongs 80 also impart mechanical support for the motor drive assembly 52, in the manner described hereinabove in connection with Figs. 2 and 3.

The electromagnetic clutch 76 may be of any preferred construction, the illustrated arrangement corresponding to that shown in Patent No. 2,267,114. Clutch 76 comprises a winding 90 generating magnetic flux through drive disk 91 and driven disk 92 around a non-magnetic region 93. Abrupt starting and stopping of the low inertia driven disk 92 is effected by this arrangement, resulting in accurate positioning control of the driven loop antenna and associated indicators.

A further important advantage of the disclosed arrangement of the motor drive mounted within chassis unit 15 is the normal temperature range it is subjected to during flight conditions. The prior motor drive arrangements were at the loop antenna, and were subjected to the extreme variations in temperature that the externally mounted loop was subjected to. The more normal temperature variations on the motor afford greater reliability and stability of operation. Furthermore, the motor when placed in unit 15 is far more accessible for servicing and maintenance. The ready mechanical and electrical mounting and demounting feature of the motor greatly enhances its serviceability. The prongs 80 of the motor drive unit preferably are mechanically biased or arranged with respect to 75

socket members 82 to predetermine the circuit connections of motor unit 52 with the circuits of unit 15.

Although a preferred arrangement of the invention has been described and illustrated, it is of course subject to variation and modification in practice as will be understood by those skilled in the art. It accordingly is not intended to limit the spirit and scope of the invention, except as set forth in the following claims.

What I claim is:

1. A radio direction finder system comprising a rotatable directional antenna, an electric circuit control unit positioned remotely from said antenna, said remote unit containing a reversible electric motor drive mounted therewith, a flexible mechanical shafting having one end connected to the output of said motor drive, a multiple coupling member connected to said shafting, a quadrantal error corrector coupled with said directional antenna, a plurality of indicators and individual flexible shafts extending from said member and mechanically connecting said corrector and said indicators in operative relation with said antenna and drive.

2. A radio direction finder system comprising a rotatable directional antenna, an electric circuit control unit positioned remotely from said antenna, said remote unit containing an electric motor drive and integrally mounted reduction gearing, a mechanical shaft extending from the low speed output of said gearing, a multiple coupling member connected to said shaft, said member having individual detachable flexible connecting cables extending therefrom, and a plurality of 360° bearing indicators, said indicators and antenna being individually operatively connected with said extending cables in proper relative bearing relation.

3. A radio direction finder system comprising a rotatable directional antenna, a radio and electrical circuit control unit positioned remotely from said antenna and containing an electric motor drive mounted therewith, a flexible mechanical connection between said motor drive and the remotely positioned directional antenna including a 1:1 gearing coupling member having detachable connecting pieces, a quadrantal error corrector between said mechanical connection and said directional antenna, and a plurality of bearing indicators mechanically coupled to said member.

4. A radio direction finder system comprising a rotatable directional antenna, a radio and electrical circuit control unit positioned remotely from said antenna, said remote unit containing a tunable radio portion and an electric motor drive, a tuning control head remote from said unit comprising a movable scale tuning indicator and a rotatable tuning member coupled with said scale, a flexible mechanical shaft connecting said rotatable tuning member with said tunable radio portion for remotely effecting tuning control of the system, separate direction bearing indicating means, and a multiple coupling member having individual extending flexible shafts operatively coupling said motor drive, said antenna, and said indicating means.

5. In a radio direction finder system having a rotatable directional antenna and an electrical control circuit unit with a socket, a motor drive for said antenna arranged in a unitary structure comprising an electric motor, an electromagnetic clutch, reduction gearing, and a plurality of metallic prongs extending from a base of said mo-

tor drive, said prongs being circuitally connected with electrical components of the motor drive for removably plugging the motor drive into said socket in mechanical position on said unit, said socket having coating elements in circuit with said unit whereby said motor drive is also placed in predetermined circuital relation therewith.

6. In a radio direction finder system having a rotatable directional antenna and a radio and electrical control circuit unit remotely positioned from said antenna, a motor drive for said antenna comprising a plurality of conductive mechanical elements secured with the motor, conductive members on said unit in circuit connec-

tion with the electrical circuit portion thereof and engageable with said elements, said elements being connected with electrical components of the motor and arranged for removably plugging the motor drive into electrical circuit relation with said unit and into mechanical position therewith, electrical circuit connections between said rotatable antenna and the radio circuit portion of said unit, and a flexible mechanical cable operatively mechanically connecting said antenna with the mechanical output of the remote removably pluggable motor drive.

WILLIAM P. LEAR.
